CODED TRACK CIRCUIT SIGNALING SYSTEM

Thomas J. Judge, Rochester, N. Y., assignor to
General Railway Signal Company, Rochester,
N. Y.

Application October 11, 1941, Serial No. 414,585

1 Claim. (Cl. 246—33)

The present invention relates to railway signaling for a comparatively short single track section connecting two double track sections, and more particularly to signaling for moving traffic in both directions over such single track section without the employment of line wires.

In view of the large expense involved in building a bridge or in building a tunnel it is quite common to build such bridge or tunnel wide enough to accommodate a single track instead of two tracks even though such bridge or tunnel is to be built for a double track railroad. Obviously, special signaling must be provided to prevent the movement of trains over this single track section in both directions at the same time.

In accordance with the present invention it is proposed to provide a signal governing the entrance of traffic into each end of the single track section extending through a tunnel or over a bridge, to provide approach sections to the rear of each of these signals, to provide a dual track circuit having a track relay at each end thereof for this single track section and to render only one of these track circuits effective if a particular approach section is occupied by an approaching train. More specifically, it is proposed to normally connect a source of energy to each end of the single track section and to substitute a track relay for this source of energy at a particular end of the single track section when the adjacent approach section becomes occupied by a train, so that this track relay may control the associated signal in accordance with conditions of traffic in the single track section and the approach section located beyond such single track section in advance of the signal.

Other objects, purposes and characteristic features of the present invention will be pointed out in the specification hereinafter when considered in the light of the accompanying drawing, in which drawing:

Fig. 1 shows a single track section of railway connecting two double track sections signaled in accordance with the present invention; and

Fig. 2 illustrates how the several kinds of sources of current are derived from a single source of alternating current.

Structure

Referring to Fig. 1 of the drawing the illustration represented by the reference character TU constitutes a tunnel through a mountain or a bridge extending over a stream, which bridge or tunnel is only wide enough to accommodate a single track section of railroad and which has

been designated TS. The left-hand end of this single track section TS is provided with a signal S1 for governing east-bound traffic into the section and the east end of this single track section is provided with a signal S2 for governing west-bound traffic into the single track section. These signals may be of any suitable construction and may constitute either a semaphore signal, a multiple aspect color light signal, or a movable spectacle search-light signal, and for convenience only a multiple aspect color light signal has been illustrated. As shown these signals are provided with a proceed lamp Y and a stop lamp R it being understood that a train moving over a bridge or through a tunnel should proceed at limited speed as is permitted by the caution signal unit Y. To the rear of the signal S1 has been provided an approach section AT and to the rear of the signal S2 has been provided an approach section BT. These approach sections AT and BT are provided with track relays ATR and BTR, respectively, and are located at the end of the approach section adjacent the signals S1 and S2, respectively. These approach track relays ATR and BTR are connected to full-wave rectifiers AR and BR, respectively, energized from track transformers TRA and TRB, respectively. The opposite ends of these approach sections AT and BT are provided with the usual track transformer TRAS and TRBS, respectively, which transformers are energized from an alternating current transmission line, the secondary windings of these transformers are provided with the usual series resistance 10 and 11, respectively. It is readily understood that under normal conditions with the approach sections AT and BT unoccupied the track relays ATR and BTR will be energized. Although as illustrated the approach track sections AT and BT are normally continuously energized causing their track relays to continuously assume their energized position, it should be understood that these approach track sections may be energized by coded current in which event code following track relays controlling de-coding apparatus will be employed, such, for instance, as is employed in the single track section TS which will be presently described.

Across the rails of the left-hand end of the single track section TS is connected one winding of a track transformer TR1, whereas a similar winding of a track transformer TR2 is connected across the track rails at the east end of this single track section TS. These transformers TR1 and TR2 at times apply energy to the track section and at other times receive energy from

the track section. Under normal traffic conditions (no trains present) both of these transformers apply energy to the track section TS. The other winding of these transformers TR₁ and TR₂ are normally connected through front contacts of the associated approach track relay to a source of coded current. Since the apparatus at both ends of the single track section TS are identical the apparatus at the west end of this single track section will be specifically described, like reference characters having distinctive exponents, prefixes or suffixes being employed to signify like devices at the east end of this single track section TS.

The track transformer TR₁ is connected to a source of alternating current BX-NX (see Fig. 2) through front contacts 14¹ and 15¹ of the approach track relay ATR, through the series resistance 16¹, the front contact 17¹ of the relay 1FRP and through the contact 18¹ of the coder 1CT. This coder 1CT may be of any suitable construction such as a motor operated rotary contact or an oscillator device having a contact 22¹ which is intermittently closed by oscillation, the construction being such that this contact is closed, say 120 times per minute. Both of these types of coders are well known in the art and therefore the coders 1CT and 2CT are illustrated conventionally. The coding device 1CT is electrically controlled and as shown is normally energized through a front contact 19¹ of the approach track relay ATR. The relay 1FRP is a normally energized relay which is energized through a circuit closed when the decoding apparatus, presently to be described, manifests danger traffic conditions, that is, this relay is energized through a circuit including back contacts 20¹ and 21¹ of the front and back repeater relays 1FP and 1FBP, respectively.

When the approach track relay ATR is de-energized, as would be the case when the approach track section AT is occupied, the free winding of the transformer TR₁ is disconnected from the coding apparatus and is connected to suitable decoding apparatus through the medium of back contacts 14¹ and 15¹ of the approach track relay ATR. This decoding apparatus consists of a code following track relay 1T energized through a series resistance 24¹ and a full-wave rectifier 1R and includes front and back repeater relays 1FP and 1FBP. This code following track relay 1T is provided with a code following contact 25¹ which when in its energized position closes an energizing circuit for the slow dropping front repeater relay 1FP and which when in its retracted position closes an energizing circuit through the front contact 26¹ of the relay 1FP and through the winding of the slow dropping back repeater relay 1FBP. These slow dropping relays 1FB and 1FBP are each made slow dropping in any suitable manner as, for instance, by the provision of slugs of conducting material of low resistance surrounding their cores, as indicated by the shaded area, and by being short circuited by reversely poled half-wave rectifiers as illustrated. These repeater relays 1FP and 1FBP are energized from a source of direct current having terminals BL and CL, which source, as shown in Fig. 2 of the drawing, is derived from a full-wave rectifier R energized from an alternating current source.

As illustrated the signal S1 is normally a dark signal because the approach contact 27¹ comprising a back contact of the approach track relay ATR is normally open, but this signal will

be illuminated upon closure of the approach contact 27¹ and will assume the proceed caution condition, in which the lamp Y is energized, if the front contact 28¹ of the front and back repeater relay 1FBP is then closed, but will indicate danger by the illumination of the red lamp R if this contact 28¹ then assumes its retracted position. The apparatus at the east end of the single track section TS is identical to that at the west end of this single track section as just described and for this reason the devices at the east end of the section have been designated by like reference characters having distinctive exponents, prefixes or suffixes.

Operation

From the foregoing it is apparent that under normal clear traffic conditions both of the approach track relays ATR and BTR are energized and by the closure of their respective front contacts 14¹-15¹ and 14²-15² will apply coded current to both ends of the single track section TS and will disconnect both of the code following track relays 1T and 2T from the track circuit so that the de-coding apparatus will be deenergized and will cause their associated signals to indicate danger traffic conditions if the approach contacts 27¹ and 27² were to be closed which they cannot be. That is, these approach contacts 27¹ and 27² are open because they are back contacts of the normally energized approach track relays ATR and BTR, respectively.

Let us now assume that an east-bound train approaches on one of the two tracks connected through the medium of the track switch Sw1 to the left-hand end of the approach section AT. As soon as this train passes over the points of the track switch Sw1 and onto the approach track section AT the wheels and axles of this train cause deenergization of the approach track relay ATR for obvious reasons. Dropping of the track relay ATR will disconnect the coded alternating current source created by the coder 1CT and will instead connect the decoding apparatus comprising the code following track relay 1T, its back and front repeater relays 1FP and 1FBP, and associated apparatus. Assuming that the single track section TS, and the approach section BT next in advance thereof with respect to the signal S1, is unoccupied, under this condition the code following track relay 1T will pick up and drop away 180 times per minute in response to the coded current applied to the east end of this single track section TS, resulting in the continuous energization of the back and front repeater relays 1FP and 1FBP, respectively. With these relays 1FP and 1FBP, or either of them, in their energized condition the check relay 1FRP is de-energized and upon dropping away opens the check contact 11¹. This check relay 1FRP assures against the application of a code at the west end of the track section TS in the event either of the relays 1FP or 1FBP should fail to drop upon discontinuation of the received code. With the front and back repeater relay 1FBP continuously energized and with the approach track relay ATR deenergized, due to its occupancy by the east-bound train, an energizing circuit for the caution lamp Y is closed, which circuit may be traced from a terminal BX of a source of alternating current, through back contact 21¹ of the approach track relay ATR, through front contact 28¹ of the front and back repeater relay 1FBP through the lamp of the signal unit Y to the other terminal NX. The east-bound train

on the approach section AT may therefore proceed into the single track section TS under conditions authorized by the illumination of the yellow lamp Y of the signal S1.

The entrance of the east-bound train upon the single track section TS will, of course, cause continuous deenergization of the code following track relay 1T and will cause the signal S1 to assume its stop condition in which condition its red aspect R is illuminated. When the rear end of the train leaves the approach section AT the approach contact 27¹ opens and the signal S1 is extinguished. As the east-bound train proceeds through the single track section TS and enters upon the approach section BT no change in traffic condition as manifested by the signal S1 takes place, and if approach contact 27¹ were closed the signal S1 would still indicate stop. Also, when the east-bound train under consideration has passed entirely out of the track section TS and occupies the approach section BT, no change in the signal aspect of the signal S1 takes place, that is, this signal S1 would continue to give a danger signal indication by the illumination of its red lamp R if the approach contact 27¹ were closed, because the presence of the east-bound train on the approach section BT causes deenergization of the approach track relay BTR which results in disconnecting the coding circuit including the coding contact 18² of the coder 2CT from the east end of the single track section TS, so that no coded current can reach the decoding apparatus at the west end of the single track section TS. There is another reason why the signal S1 will not indicate proceed even if the approach contact 27¹ were closed and that is because the approach track relay ATR which is now assumed to be in its energized condition disconnects the decoding apparatus including the code following track relay 1T and its front and back repeater relays 1FP and 1FBP from the west end of the track rails of the single track section so that front contact 28¹ of relay 1FBP remains open. Attention is directed to the fact that signal S2 clears as soon as the east-bound train has entirely passed it. This is based on the assumption that the single track section TS and the approach section AT in advance thereof are unoccupied. This clearing of the signal S2 is in part due to the fact that approach section BT is occupied to cause closure of approach contact 27². As soon as the east-bound train passes off of the approach section BT and over the track switch Sw2 into one of the tracks of the double track section connected by switch Sw2 to approach section BT, all of the apparatus returns to its normal condition heretofore described. The apparatus is symmetrical and functions identically the same for a west-bound train movement over the track illustrated as for an east-bound train movement.

The applicant has thus provided signaling apparatus for a single track section in which coded current is normally applied to both ends of a single track section and in which decoding apparatus is substituted for the code applying apparatus at a particular end of such single track section when a train is about to enter that end of the single track section, the presence of the

train being manifested through the medium of an approach section. Although code is applied to both ends of the single track section at the same time and although the application of these codes to opposite ends of the same single track section may cause what is commonly known as a "code fight," this code fight is of no material importance because there are no code following track relays or decoding apparatuses connected to the ends of a single track section under the condition assumed. As soon as one of the decoding track relays is connected to the single track section no code fight can exist because simultaneous with such connection of the code following track relay and associated apparatus the code applying apparatus at that end of said section is disconnected. It is, of course, understood that the particular system which has been illustrated has been selected for the purpose of describing the present invention with the view of disclosing the underlying principles of the invention by apparatus embodying the invention and the functions accomplished by such apparatus and that this particular embodiment of the invention has not been illustrated to show all forms that the invention may take and that various changes, modifications, and additions may be made to adapt the invention to the particular problem encountered in practicing the invention all without departing from the spirit or scope of the invention, except as demanded by the scope of the following claim.

What I claim as new is:

In combination, a stretch of track, an approach section adjacent each end of said stretch over which approaching trains moving in opposite directions may enter said stretch, two intermittently closed coding contacts one at each end of said stretch, a source of current at each end of said stretch included in series with the associated coding contact, a code following track relay for each end of said stretch, decoding means controlled by each of said code following track relays and rendered active when the associated code following track relay follows the impulses of a code, a signal at each end of said stretch for governing the movement of traffic into said stretch from that end and controlled by the associated decoding means, a track circuit for each approach section including an approach track relay at the end adjacent said stretch, contacts controlled by each of the approach track relays of the approach sections for connecting the source of current and the coding contact included in series therewith to that end of the track rails of said stretch when the adjacent approach track relay assumes its energized position and disconnecting said source of current and the coding contact included in series therewith and connecting the code following track relay at that end of said stretch to the track rails at that end of said stretch when the adjacent approach track relay assumes its deenergized position, and checking means for preventing the application of a code to a particular end of said stretch of track when the decoding means at that end of said stretch assumes its active condition.

THOMAS J. JUDGE.
